DESIGN FOR A TEXTILE FABRIC

Curt E. Forstmann, Montclair, N. J.

Application October 12, 1938, Serial No. 80,417

Term of patent 3½ years

To all whom it may concern:

Be it known that I, Curt E. Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design is characterized by a narrow series of stripes running at right angles to another series of stripes comprising solid bars substantially uniformly spaced end to end, the stripes of the other series of stripes comprising ladder-like bars substantially uniformly spaced end to end, the bars of one series of stripes passing through the spaces between the bars of the stripes of the other series at the points of intersection as shown.

I claim:

The ornamental design for a textile fabric, as shown and described.

CURT E. FORSTMANN.
